JOSEPH HORSTE, OF DETROIT, MICHIGAN, ASSIGNOR TO DETROIT HARVESTER COMPANY, OF DETROIT, MICHIGAN, A CORPORATION OF MICHIGAN

DRILLING MACHINE

Application filed June 17, 1929. Serial No. 371,619.

This invention relates generally to drilling machines such as those designed for forming sockets, recesses or openings in metal objects, and consists of certain novel features of construction, combinations and arrangements of parts that will be hereinafter more fully described and particularly pointed out in the appended claim.

In the accompanying drawings:

Figure 1 is a fragmentary top plan view of a machine embodying my invention;

Figure 2 is a fragmentary vertical sectional view taken on the line 2—2 of Figure 1;

Figure 3 is an enlarged end view of the worm gear and associated parts and showing portions of the table in section;

Figure 4 is a diagrammatic view of the gear mechanism and associated parts including the clutch mechanism;

Figure 5 is a sectional view through the plunger adjusting means;

Figure 6 is a fragmentary sectional view through one of the plungers and associated gears.

Referring now to the drawings, 1 is a metal object constituting the work and 2 is the machine embodying my invention. In practice the metal object 1 may be any suitable design or metal part, and a plurality of such objects may be drilled simultaneously by my machine.

Referring to the machine illustrated in the accompanying drawings, 10 is a horizontal frame or table, 11 are laterally spaced plungers mounted to reciprocate and rotate in brackets 12 on the table, and 13 are drills at the forward ends of the plungers for engagement with the work, 15 designates generally the work holding means, 16 are cam followers movable longitudinally of the plungers, 17 is a rotary shaft extending across and journaled in brackets 18 on the table adjacent to said followers 16, 19 are cams rigid with the shaft 17 engaging the followers 16 and adapted when said shaft is rotated to reciprocate said plungers 11 and drills, 20 is a train of gearing for rotating said cam shaft, 21 is a train of gearing for rotating said plungers 11, and 22 designates

generally a clutch control for said trains 20 and 21 of gearing.

As shown, the drills 13 are detachably connected by suitable coupling members 23 and 24 respectively to the plungers 11, and the followers 16 for actuating the latter are yieldingly held by springs 25 in engagement with the cams 19. Preferably, the followers 16 are adjustable longitudinally of the plungers 11 to regulate the reception or longitudinal movement of the plungers 11 and thereby control the depth of cut by the drills 13. In the present instance this is accomplished by providing three collars 26, 26' and 26" respectively on each plunger 11 between the follower 16 and spring 25. Preferably the collars are sleeved loosely upon the plungers and have rearward extensions 27, 27' and 27" respectively. The followers 16 are sleeved upon and have a press fit with the extensions 27, while the collars 26 and 26' have sockets 28 and 28' that receive and are threadedly engaged by the extensions 27' and 27" respectively. Thus, with this construction the collars 26, 26' and 26" may be adjusted longitudinally of the plungers 11 and may be held in such adjusted position by set screws 29, 29' and 29".

With this construction, the metal objects 1 to be drilled are provided with laterally spaced openings 7 that receive pegs 30 projecting laterally from an upstanding transversely extending part 31 of the frame or table so that such objects will be in proper position relative to the drills 13. Followers 32 sleeved on rods 33 projecting laterally from the part 31 of the table hold the objects constituting the work on the pegs 30. As shown, cams 34 rotatably mounted on cross rods 35 carried by the rods 33 are adapted to be actuated by levers 36 to engage the followers 32 and hold the same in operative position against the work, while coil springs 37 sleeved on the rods 33 between the part 31 and the followers 32 are adapted when the cams 34 are released to automatically return the followers 32 to inoperative position. Preferably the bushings 40 are provided for guiding the drills 13 into proper engagement with the work. As shown,

these bushings are secured in suitable openings in the frame part 31 and have central bores 30' that receive and guide the drills 13.

With this construction the shaft 17 is provided at one end with a gear 41 that is adapted to be actuated by a worm 42 on a stud shaft 43 carried by suitable arms 44 and 45 respectively depending from the table. A gear 46 is rigid with the shaft 43 and is adapted to be driven by the train 20 of gears that lead to the main driving shaft 47 from the motor (not shown). Likewise, the plungers 11 are rotated to cause the drills 13 to rotate to obtain the proper drilling action. To accomplish this I have provided a set of gears 50 that are splined upon the plungers 11 at the rear ends thereof between the bearings 12 and frame part 12', and are adapted to be rotated by the train 21 of gearing that is also operated by the motor shaft 47. Preferably, the motor shaft 47 is located between the trains 20 and 21 of gearing and carries a main driving gear 51 that constitutes a common actuating means for said trains 20 and 21. Moreover, the clutch mechanism 22 is associated with the shaft 47 and is adapted to control the operation thereof. As shown, the clutch proper 53 is of conventional form and is actuated by a longitudinally movable rod 54 under the control of an operating handle 55. Links 56 and 57 constitute an operative connection between the handle shaft 58 and the rod 54. 59 is a bearing for the rod 54. Thus, the clutch on the shaft 47 serves as a common control for both trains 20 and 21 of gearing.

In order that the drills 13 and the work, such as the objects 1, may be maintained cool while being drilled, water is conveyed from a suitable source through pipes 60 and 61 to registering openings 62 and 63 respectively in the frame part 31 and bushings 40 to the drills 13 and may be collected in a suitable trough 64.

Thus, from the foregoing description, it will be apparent that a plurality of metal objects such as 1 may be drilled simultaneously and such objects and drills may be effectively cooled. In fact, the drills and the work are more effectively cooled since the cooling fluid is conveyed through the drill bushings 40 to the point of contact with the work. Another important feature is the construction and arrangement of the collars 26, 26' and 26'' on the plungers 11, enabling adjustments to be made even while the machine is in operation to regulate the cutting operation of the respective drills.

While it is believed that from the foregoing description, the nature and advantage of my invention will be readily apparent, I desire to have it understood that I do not limit myself to what is herein shown and described and that such changes may be re-

sorted to when desired as fall within the scope of what is claimed.

What I claim as my invention is:

In a machine of the class described, the combination with a drill, of actuating means therefor including a plunger mounted for longitudinal and rotary movement, means for moving said plunger longitudinally including a rotary cam, relatively adjustable collars on said plunger, one of said collars being fixed upon the spindle and having a threaded extension, another of said collars having a socket receiving the threaded extension and having a threaded extension, and another of said collars having a socket receiving the last mentioned extension and having a smooth extension, a cam follower pressed upon the smooth extension whereby the follower is adjustable with respect to the spindle, and yieldable means associated with said collars for maintaining said follower in operative engagement with said cam.

In testimony whereof I affix my signature.

JOSEPH HORSTE
